Primary Examiner — Ian Simmons*Assistant Examiner* — Eleni H Aldridge(74) *Attorney, Agent, or Firm* — Novak Druce Connolly Bove + Quigg LLP(57) **CLAIM**

The ornamental design for a ladle, as shown and described.

DESCRIPTION

FIG. 1 is a perspective view of the ladle;

FIG. 2 is top plan view of the ladle;

FIG. 3 is a cross-sectional view of the ladle along 3-3 of FIG. 2;

FIG. 4 is a bottom plan view of the ladle;

FIG. 5 is a front side view of the ladle of FIG. 2, with the rear side view being identical;

FIG. 6 is a right side view of the ladle of FIG. 2; and,

FIG. 7 is a left side view of the ladle of FIG. 2.

The portions represented by broken lines form no part of the claimed design.
